UNITED STATES PATENT OFFICE.

JOHN H. KISSINGER, OF SPOKANE, WASHINGTON.

CORKSCREW.

1,110,210.

Specification of Letters Patent.

Patented Sept. 8, 1914.

Application filed October 3, 1913. Serial No. 793,227.

To all whom it may concern:

Be it known that I, JOHN H. KISSINGER, a citizen of the United States, residing at Spokane, in the county of Spokane and State of Washington, have invented new and useful Improvements in Corkscrews, of which the following is a specification.

This invention relates to cork extractors and has particular reference to devices of this character wherein a fulcrum arm is employed for engagement with the mouth of the bottle so that a leverage may be formed to enable a cork to be readily started from the neck of the bottle after the cork screw has been inserted in the cork.

The primary object of the invention is the provision of a device of the above mentioned character so constructed that the said fulcrum arm may be adjusted to different positions upon the lever, so that the former will always be arranged perpendicular with respect to the latter whereby a more direct pressure is obtained when the device is used with bottles of different diameters.

Another object of the invention is the provision of a device of the character described wherein the said fulcrum arm is provided with a ring adapted to embrace the neck of the bottle so that the pressure applied to the lever will be equally distributed around said neck to facilitate the removal of the cork.

A further object of the invention is the provision of a device of the class in question wherein the fulcrum arm and cork screw may be locked in folded position when not in use between the members forming the lever.

A still further object of the invention is the provision of a device of the above mentioned character which is simple in construction, cheaply manufactured, and readily and easily manipulated for the purpose intended.

In the drawing forming a portion of this specification and in which like numerals of reference indicate similar parts in the several views; Figure 1 shows the device in side elevation and the manner of using the same. Fig. 2 is a view of a modified form showing the manner of using the same. Fig. 3 is a longitudinal sectional view of the device. Fig. 4 is a view of the device showing

the fulcrum arm and cork screw folded. Fig. 5 is a section taken on line 5—5 of Fig. 4.

Referring to the drawing by numerals 1 designates a pair of spaced parallel members forming a handle and serving in the capacity of a lever as will hereinafter be more fully described. Each of the said members are curved upwardly as at 2 and extended forwardly as at 3, the said forwardly extending portions being longitudinally slotted for the major portion of their length as at 4. Adjacent the curvature 2 of each of the said members are provided with an alined opening 5 in which are journaled the free ends of the pin 6 which projects from the opposite sides of the body portion 7 of the cork screw 8. The body portion 7 of the cork screw is of rectangular formation and pivoted by means of the pin 6 between the members 1, and by means of which the said members are held in proper spaced relation. The cork screw 8 is adapted to be folded between the members 1 when not in use and with a view of retaining the same in folded position, one of the said members is provided with a recess 9 for the reception of the lug 10 formed on one side 80 of the body portion 7. The upper wall of each of the said slots 4 is formed with a plurality of U-shaped alined recesses which open downwardly toward the lower wall of said slot for a purpose which will presently 85 be set forth. The fulcrum arm 11 is disposed between the said forwardly extended portions 3 and adjustably mounted within the slot 4 thereof by means of the pin 12 extending transversely through the arm and 90 having its free ends 13 projecting from the opposite sides thereof and bearing on the lower wall of the slots 4. By reason of this construction it will be manifest that when using the device the fulcrum arm 11 may be 95 adjusted along the lower wall of the slots 4 to different positions upon the lever so that the said arm may be arranged perpendicular with respect to the said lever whereby a more direct pressure is obtained, and to 100 permit of use of the device with bottles of different diameters. The lower end of the arm is formed with a groove 14 adapted to be fitted on the upper edge of the bottle

neck when the device is in use as indicated in Fig. 1.

In use of the device the cork screw is first inserted in the cork or stopper of the bottle, 5 after which the lever is lowered to permit the fulcrum arm 11 to be moved into engagement with the upper edge of the bottle neck. The lever is then raised, causing the free ends of the pin 12 to be moved upwardly within the alined recesses of the lever. It will be obvious that as the lever is further raised a direct pressure is exerted upon the fulcrum arm and by reason of its connection with the upper edge of the 15 bottle neck the cork will be forced upwardly until the same is removed from the bottle. By reason of the particular formation of the lever together with the relative arrangement of the extracting element and the fulcrum 20 arm, not only a more direct pressure is obtained but also a maximum leverage without unduly increasing the length of the lever.

The fulcrum arm is adapted to be folded 25 over and between the forwardly extended portions 3 when not in use and in order to retain the arm in folded position I provide one of the members 1 adjacent the curvature 30 2 thereof, with a curved slot 15 which opens at the upper edge of said member and is adapted to receive the lug 16 formed on the fulcrum arm adjacent the lower end thereof.

In Fig. 2 I have shown a modified form 35 of the fulcrum arm which as will be noted is formed at its lower end to provide a ring 17 which is adapted to embrace the neck of the bottle so that the pressure exerted upon the said fulcrum arm will be equally 40 distributed around the neck thus facilitating the removal of the cork from the bottle when the lever is raised. It will be understood that the pressure exerted by the ring is in a vertical direction and that the breaking 45 of the neck need not be feared.

With the foregoing description taken in connection with the accompanying drawing it will be manifest that I have provided a cork extractor which is extremely simple in 50 construction and which may be readily and easily manipulated for use in conjunction with different size bottles. While I have shown and described the preferred form of my invention it is to be understood that I

am not to be limited to the precise construction and arrangement herein shown, as various changes may be made within the scope of the appended claims.

What I claim is;

1. A cork screw comprising spaced parallel members forming a lever, each of said members being curved upwardly adjacent one end and having a portion extended forwardly therefrom, said forwardly extended portions having longitudinally disposed 65 slots, the upper wall of said slots being formed with alined recesses opening in a downward direction, an arm adjustable in said slots and adapted for interchangeable engagement with said recesses, said arm 70 forming a fulcrum for said lever, and a cork screw pivoted between said members rearwardly of said arm as described.

2. A cork extractor comprising a lever of substantially U-form having an upwardly 75 and forwardly extending bifurcated end portion, the parallel members of said bifurcated end portion having alined longitudinally disposed slots, the upper wall of each slot being provided with downwardly opening 80 recesses; an extracting element pivoted to said lever below said bifurcated end portion, a fulcrum arm supported by and slidably adjustable on the lower walls of said slots and adapted for interchangeable 85 engagement with said recesses for the purpose specified.

3. A cork extractor comprising a lever formed from sheet metal into substantially 90 U-form and having upwardly and forwardly extending bifurcated end portions, an extracting element pivotally supported on said lever below said bifurcated end portion and adapted to be folded rearwardly between the parallel side members of the lever; a fulcrum arm pivotally mounted between the members of said bifurcated end portion and adapted to be swung upwardly and over 95 between said members to folded position, and means for retaining said element and 100 arm in folded position.

In testimony whereof I affix my signature in presence of two witnesses.

JOHN H. KISSINGER.
